CLAIM

We claim the ornamental design for an ultrasound cart, as shown and described.

DESCRIPTION

FIG. 1 is a perspective view of an ultrasound cart;
FIG. 2 is a front view of the claimed design shown in FIG. 1;
FIG. 3 is a rear view of the claimed design shown in FIG. 1;
FIG. 4 is a left side view of the claimed design shown in FIG. 1;
FIG. 5 is a right side view of the claimed design shown in FIG. 1;
FIG. 6 is a top view of the claimed design shown in FIG. 1; and,
FIG. 7 is a bottom view of the claimed design shown in FIG. 1.
The broken lines illustrate portions of the ultrasound cart that form no part of the claimed design.

1 Claim, 7 Drawing Sheets
